UNITED STATES PATENT OFFICE.

JOSEPH F. LAMB, OF NEW BRITAIN, CONNECTICUT, ASSIGNOR TO LANDERS, FRARY & CLARK, OF NEW BRITAIN, CONNECTICUT, A CORPORATION OF CONNECTICUT.

EYE-SHIELD AND SECURING MEANS THEREFOR.

1,289,482.

Specification of Letters Patent. Patented Dec. 31, 1918.

Application filed March 20, 1918. Serial No. 223,677.

To all whom it may concern:

Be it known that I, JOSEPH F. LAMB, a citizen of the United States, and a resident of New Britain, in the county of Hartford, 5 State of Connecticut, have invented certain new and useful Improvements in Eye-Shields and Securing Means Therefor, of which the following is a specification.

This invention relates to improvements in 10 eye shields, or similar devices, and means for securing them in place.

In the drawings—

Figure 1 is a front view of a section of fabric in which an eye shield is secured.

15 Fig. 2 is a sectional view on the line of 2—2 of Fig. 1 but on enlarged scale.

Referring to the drawings—A denotes a fabric or other material or structure in which the shield may be secured. 1 20 5 denotes generally the shield frame of annular form and reduced in diameter at one end with its edge flared out as at 6, to provide an exterior annular channel. The fabric has an aperture smaller than the reduced 25 end of the frame, its edge being slit to receive the frame and provide enough material to fold into the channel. The fabric at the edge of the aperture may be reinforced if desired as indicated at b. A securing spring 10, which may be snapped into the channel, has a bearing over a considerable area of the fabric, securely positioning the frame in place. For the purpose of easy removal of the spring when 30 necessary, the wire from which it is made may be relatively soft, so that a metal point can be caught into the spring and the spring distorted permanently making its removal 35 easy.

40 The reduction in diameter of the frame provides a shoulder 15, which as seen is preferably slightly inclined outwardly, and against this shoulder is located a gasket 16; the eye shield 17, which may be of celluloid or some similar transparent material, lies against this gasket. The wall of the frame 1 is threaded, a securing ring 20, has threaded engagement therewith and is provided with an inturned flange 21, which has 45 a slight annular bead or projection 22, to engage the edge of the shield 17. As the securing ring 20, is screwed down into place it engages the outer edge of the shield 17, back of the raised edge of the shoulder 15, 50 This results in stretching the eye piece tautly.

over the opening and provides a secure grip for the edge of the eye piece, the effect of which may be substantially increased by the provision of the annular bead or projection 22. 60

In accordance with the provisions of the patent statutes I have described the principle of operation of my invention, together with the apparatus which I now consider to represent the best embodiment thereof, but 65 I desire to have it understood that the apparatus shown is only illustrative, and that the invention can be carried out by other means.

I claim as my invention—

1. In a device of the character described 70 an annular frame provided with a shoulder, a gasket set against said shoulder, a shield member resting against said gasket, a securing ring engaged with said frame and provided with an inturned flange, and a projection on said flange for engaging said shield member.

2. In a device of the character described 75 an annular frame provided with an outwardly inclined shoulder, a gasket positioned against said shoulder, a shield member with its edge resting on said gasket, and a securing ring engaged with said frame and adapted to bind said shield member 80 against said shoulder.

3. In a device of the character described, 85 an annular frame provided with an outwardly inclined shoulder, a shield member fitting within said frame and with its edge overlying said shoulder, a securing ring engaged with said frame and provided with an inturned flange opposite said shoulder, and projections on said flange engaging the edge of said shield member to bind it against 90 said shoulder.

4. In a device of the character described 100 an annular frame having at one end a portion of reduced diameter the end of which is outwardly flared to provide an exterior annular channel, a fabric apertured to receive said reduced portion with the edge of the fabric at the aperture folded into the bottom of said annular channel, a spring member fitted into said annular channel and 105 lying against said fabric to secure it to said frame, an annular shoulder formed in said frame by said reduced portion, a shield member fitted within said frame and with its edge overlying said shoulder, and a se- 110

curing ring engaged with said frame and having an inturned flange between which and the said shoulder the edge of said shield member is positioned and clamped.

5. In a device of the character described an annular frame provided at one portion with an exterior circumferential channel, a fabric apertured to receive said portion with the edge of the fabric folded into the bot-

tom of said channel, and a ring-shape coil 10 spring normally of smaller diameter than the bottom of said channel but adapted to be sprung into said channel to securely bind the fabric in place, said spring being made of relatively soft wire to permit of easily 15 stretching it to facilitate its removal from the channel.

JOSEPH F. LAMB.
